UNITED STATES PATENT OFFICE

103,541

DESIGN FOR AN AIR CONDITIONING CONTROL

Raymond E. Patten, Bridgeport, Conn., assignor
to General Electric Company, a corporation of
New York

Application January 15, 1937, Serial No. 67,077

Term of patent 14 years

To all whom it may concern:

Be it known that I, Raymond E. Patten, a citizen of the United States, residing at Bridgeport, in the county of Fairfield and State of Connecticut, have invented a new, original, and ornamental Design for Air Conditioning Control, of which the following is a specification, reference being had to the accompanying drawing, forming a part thereof, and in which

Figure 1 is a perspective view of an air conditioning control embodying my new design looking from above and to the left, and

Figure 2 is a perspective view of the same looking from below and to the right.

I claim:

The ornamental design for an air conditioning control, substantially as shown.
